(57) CLAIM

The ornamental design for a flexible, elastic linen strap with pouch for scented potpourri, as shown and described.

DESCRIPTION

FIG. 1 is a front elevational view of the flexible, elastic linen strap with pouch for scented potpourri illustrating my design.

FIG. 2 is a rear elevational view thereof.

FIG. 3 is a left side elevational view thereof.

FIG. 4 is a right side elevational view thereof.

FIG. 5 is a top elevational view thereof; and,
FIG. 6 is a bottom elevational view thereof.

The broken lines in the drawing are shown to represent stitching on the flexible, elastic linen strap with pouch for scented potpourri.
